BOAT PROPELLING MECHANISM

Melvin Marcum and Richard Vance, Breeden, W. Va., assignors, by direct and mesne assignments, of one-sixth to J. Floyd Harrison, and one-sixth to J. T. Lambert, both of Wayne, W. Va.

Application July 24, 1941, Serial No. 403,924

1 Claim. (Cl. 115—31)

The present invention relates to new and useful improvements in boat propulsion and has for its primary object to provide, in a manner as hereinafter set forth, a mechanism comprising a novel construction, combination and arrangement for pushing, pulling and steering a hull in the water.

Other objects of the invention are to provide a boat propelling mechanism of the character described which will be comparatively simple in construction, strong, durable, highly efficient and reliable in use and which may be produced at low cost.

All of the foregoing and still further objects and advantages of the invention will become apparent from a study of the following specification, taken in connection with the accompanying drawings wherein like characters of reference designate corresponding parts throughout the several views, and wherein:

Figure 1 is a top plan view of a boat which is provided with a propelling mechanism constructed in accordance with the present invention.

Figure 2 is a view in longitudinal section, taken substantially on the line 2—2 of Figure 1.

Figure 3 is a view in rear elevation of one of the propellers.

Figure 4 is a view in vertical longitudinal section through one of the propellers.

Figure 5 is a detail view in side elevation with a portion broken away in section, illustrating the connection between one of the reciprocating rods and its crosshead.

Referring now to the drawings in detail, it will be seen that reference numeral 1 designates generally a hull of suitable construction. Mounted on the stern of the hull 1 is a plurality of pusher propellers which are designated generally by reference numeral 2. Operable forwardly of the bow of the hull 1 is a plurality of tractor or puller propellers 3. Extending diagonally and rearwardly from an intermediate portion of the hull 1 is a pair of steering propellers 4. Mounted in the hull 1 is an engine housing 5. The housing 5 encloses a single engine for the rear propellers 2, a pair of engines for the front propellers 3 and an engine for each of the steering propellers 4.

Mounted in the rear portion of the hull 1 are guides 6 in the form of longitudinal partitions which are shown to advantage in Figure 2 of the drawings. Operable in the guides 6 is a crosshead 7 which is connected by a rod 8 to an

engine in the housing 5. Journaled in the guides 6 and in the sides of the hull 1 is a crank shaft 9. A pitman 10 connects the crank shaft 9 to the crosshead 7 for actuation thereby.

Longitudinal guides 11 are provided in the stern portion of the hull 1 outwardly of the guides 6. Crossheads 12 are slidable between the guides 6 and the adjacent guides 11. Pitmans 13 operatively connect the crossheads 12 to the crank shaft 9 for actuation thereby. Threadedly connected to the crossheads 12 are reciprocating rods 14 which extend slidably through the stern 15 of the hull 1.

As best seen in Figures 3 and 4 of the drawings, the propellers 2 comprise longitudinally elongated hubs 16 of suitable material which are mounted on the rear end portions of the rods 14. At an intermediate point, the hubs 16 have formed therein chambers 17. The hubs 16 are of hexagonal cross-section, and said hubs are further provided with longitudinal grooves or channels 18 which extend rearwardly from the chambers 17.

Mounted for swinging movement on the hubs 16 are blades 19. The blades 19 include shanks 20 which are pivotally secured in the chambers 17. The grooves 18 accommodate coil springs 21 having one end secured at 22 to the rear ends of the hubs 16. The other end portions of the coil springs 21 extend into the chambers 17 of the hubs 16. The coil springs 21 cushion the blades 19 when they swing to closed position on the forward movement or stroke of the propellers 2. Resilient bumpers 23 on the forward end portions of the hubs 16 cushion the blades 19 when they swing to open position on the rearward or power stroke of the propellers 2. Coil springs 24 are connected to the blades 19 for assisting in opening said blades.

It is thought that the operation of the propellers 2 will be readily apparent from a consideration of the foregoing. Briefly, when the propellers 2 are forced rearwardly on their power stroke the blades 19 are caused to swing to open position by the water thereby pushing the boat forwardly. On the forward or return stroke of the propellers 2 the blades 19 are swung to closed position by the water thereby reducing resistance to a minimum. The steering propellers 4 are substantially similar in construction and operation to the stern or pusher propellers 2. When it is desired to turn to the left, the propeller 4 on the right hand side of the boat is actuated. When a right hand turn is to be made, the propeller 4 on the left hand side of the boat is actu-

ated. The operation of the bow propellers 3 is substantially similar to the stern propellers 2 with the exception that the construction and arrangement is such that the blades open when said propellers move rearwardly for pulling the boat through the water and close when said propellers 3 move forwardly for reducing resistance.

It is believed that the many advantages of a boat propelling mechanism constructed in accordance with the present invention will be readily understood, and although a preferred embodiment of the apparatus is as illustrated and described, it is to be understood that changes in the details of construction and in the combination and arrangement of parts may be resorted to which will fall within the scope of the invention as claimed.

5

10

15

What is claimed is:

A boat propelling mechanism of the character described comprising a reciprocating rod, means for actuating said rod, and a propeller mounted on the rod, said propeller including a longitudinally elongated hub secured to the rod and having longitudinal grooves therein, blades pivotally mounted on the hub for opening and closing movement, coil springs mounted on the hub and engaged in the grooves for cushioning the blades upon closing movement thereof, and resilient bumpers mounted on the hub for cushioning the blades upon opening movement of said blades.
